UNITED STATES PATENT OFFICE.

ASHER LAMBERT, OF NEWARK, NEW JERSEY.

FRICITION THRUST FOR LOOSE DRUMS.

No. 827,921.

Specification of Letters Patent.

Patented Aug. 7, 1906.

Application filed July 22, 1905. Serial No. 270,769.

To all whom it may concern:

Be it known that I, ASHER LAMBERT, a citizen of the United States, residing at 1 Johnson avenue, Newark, county of Essex, 5 and State of New Jersey, have invented certain new and useful Improvements in Friction Thrusts for Loose Drums, fully described and represented in the following specification and the accompanying drawings, forming a part of the same.

The present invention relates to such constructions as have a drum or spool fitted to turn loosely upon a shaft and rotated by pressure against a friction-driver which is positively driven, so as to turn the drum when engaged therewith.

In many hoisters which have a drum rotated by a friction-driver it is common to press the drum against the friction-driver by 20 means of a pin extended into the end of the drum-shaft. Means is used to force the pin longitudinally, and the end of the pin is thus subjected to heavy pressure and friction, which often causes overheating and cripples 25 the whole hoister. In some hoisters the pin is allowed to revolve with the drum-shaft and is pressed endwise by an adjustable screw. Where attempts have been made to drive the drum much above the speed ordinarily used 30 for hoisting, the end of the thrust-pin has become actually welded to the pressure-screw by the excessive heat, and the hoister has thus been completely disabled. Besides the use upon hoisting-machines for hoisting 35 with a derrick such drums are largely employed in winding the rope for "logging" and operating "cableways" to haul the load through a great distance, which consumes a great deal of time unless the drum be rapidly revolved at a much higher speed than is common in derrick-hoisting.

The speed of revolution is in practice actually controlled by the overheating and friction which are created by the great pressure upon the thrust-pin and its actuating-screw when the drum is rotated over one hundred revolutions per minute, and the usefulness of such a machine for the purpose of logging and operating cableways is enormously increased by any means which will reduce such friction and permit a higher speed. This is attained in the present invention by fixing the shaft stationary in its bearings upon the hoister-frame and fitting the friction-driver, 55 as well as the drum, to turn loosely upon the shaft and supporting the strain of pressing

the drum and friction-driver together by means of antifriction thrust-bearings applied one outside of the friction-driver and the other outside of the drum. 60

One of the antifriction thrust-bearings is fixed to the shaft and the other is movable thereon, and a nut is attached to a bearing or to one end of the shaft, in which a screw is fitted to press upon a central thrust-pin and 65 a transverse key, by which the latter thrust-bearing is forced longitudinally of the shaft to crowd the drum and friction-driver together. As the screw which produces the thrust is supported upon the stationary shaft, 70 or bearing, as well as the thrust-pin and the transverse key, there is no rotary motion to produce friction between these parts, and the drum may therefore be rotated at any desired speed without injury to these parts. 75

The thrust or friction is wholly transferred to the antifriction thrust-bearings between which the friction-driver and drum turn upon the shaft, and there is ample room upon the shaft to construct these thrust-bearings of 80 suitable magnitude to resist the thrust without injury.

The application of the invention to a hoisting-engine is shown in the drawings, in which—

Figure 1 is a plan of the hoisting-engine frame with two drums mounted thereon, one of the drums and a part of the stationary shaft being shown in section at the center line where hatched. Fig. 2 is an elevation 90 of the hoisting-engine. Fig. 3 is a side view of one of the drum-shafts with drum and friction-driver mounted to turn thereon between the thrust-bearings, the same forming a set of drum-fixtures for application to the bearings upon a hoister-frame to replace the ordinary rotary drum-shaft with friction-driver attached thereto. Fig. 4 shows the inside of one of the antifriction thrust-bearing flanges containing a ball-race with balls therein, and 100 Fig. 5 is a central cross-section of one of the thrust-bearings. Fig. 6 is a perspective view of the hoister. 105

A designates the frame of an ordinary hoister on which two steam-cylinders B are shown and a crank-shaft C, which in practice carries a pinion to mesh into the gear-wheels D upon the friction-drivers E. The friction-driver is shown as a cone of wood, and the hauling-drum F is shown formed with a hollow cone G, forming a friction-seat to engage the driver E. The shaft H of the hauling- 110

drum is shown firmly fixed in bearings I upon the frame A by means of set-screws J, and the hub K of the friction-driver is shown formed with a bushing L, which can be renewed when worn, said bushing turning with the friction-driver upon the stationary shaft H.

One of the thrust-bearings is shown fitted against a shoulder h upon the shaft H, the 10 thrust-bearing consisting of annular flanges a and b, provided each with a ball-race c, with balls d, fitted between the flanges in the races, as shown in Fig. 5. A spring M is shown encircling the hub of the friction-driver and 15 pressing at one end against the plate m of the friction-driver and at the other end against the plate f at the inner end of the drum F, thus holding the driver and drum normally out of engagement.

20 An antifriction thrust-bearing similar to that just described is shown applied to the shaft H at the outer end of the drum F, the raceway-plate a lying against the plate g, forming the outer head of the drum F and revolving with the said drum, while the raceway-plate b is held stationary with the shaft by a key N, which is inserted transversely through a slot i in the shaft H and held movably in place by pins at the opposite sides of the shaft, as is usual. (Shown in Fig. 1.) The thrust-pin O is shown inserted in a hole in the center of the shaft, which extends from the key N to the end of the shaft, and a nut is secured upon the end of the shaft by 25 forming it in a cap j, which is screwed tightly upon the end of the shaft, so as to become fixed firmly thereon. A shoulder l is shown upon the shaft adjacent to the key, which, with the inner end of the cap j, serves to hold 30 the shaft from end movement in the bearings I. The screw k is reduced upon the end to the same size as the thrust-pin, and when turned in the nut or cap j in the usual manner by hand-lever P it forces the thrust-pin 35 against the key, which presses the outer thrust-collar against the drum and engages the drum forcibly with the friction-driver.

It will be observed that all of the parts employed in crowding the drum toward the friction-driver are stationary, being thus relieved from any rotating or moving friction, as the key N, the pin O, the cap or nut j, the screw k, and the hand-lever P are held from rotation by the stationary character of the 40 shaft, while the drum and friction-driver revolve loosely upon the shaft when in operation between the two thrust-bearings.

A hoisting-drum Q is shown mounted upon a stationary shaft H', adjacent to the hauling-drum F, the hoisting-drum being much smaller than the hauling-drum, as it is intended to wind the rope with less speed and more power.

The thrust-bearings are shown operated 45 reversely upon the hoisting-drum, with the nut

j' attached to the end of the shaft-bearing next to the friction-driver, and the thrust-bearing upon the outside of the friction-driver being movable lengthwise of the shaft when the key is pressed toward it, while the 70 friction-driver upon the outer end of the hoisting-drum is fitted against the shoulder upon the shaft to prevent it from moving.

Either construction operates precisely the 75 same, although that shown in connection with the larger drum avoids any longitudinal movement of the friction-driver upon the shaft, which when the thrust-bearings are operated as shown upon the hoisting-drum moves a little outwardly when the spring M 80 disengages it from the drum.

Heretofore the shafts of hoisting-drums and analogous spools have been rotated with the friction-driver, and therefore required 85 journals and bearings fitted to turn one with- in the other and lined with antifriction metal or equivalent means of renewing the surface when worn. By my construction the shaft-bearings upon the standards R may be made 90 perfectly solid without any expense of forming caps and bolting them on and the shaft slipped endwise into the bearings by removing the cap j' or on the shaft of the drum Q.

Where a hoisting-machine has been disabled by the use of the old construction with 95 a revolving shaft and a thrust-pin revolving with the shaft, the hoister may be restored to usefulness by removing the shaft and drum with their respective fittings and inserting a shaft such as is shown in Fig. 3, with the 100 drum and friction-driver fitted to turn loosely upon the shaft between the two thrust-bearings, and the screw K, mounted in a cap or nut directly upon the end of the shaft instead of upon the bearing, as has heretofore been 105 necessary. The drum-fixtures (shown complete in Fig. 3) thus form a new article of manufacture, which may be made and applied to many hoisters of a standard type which are 110 already in use, but which frequently become disabled from the friction of the thrust-pin.

It will be understood that the nut for the 115 thrust-screw k can be bolted to or formed integral with one of the bearings, as the shaft when secured in such bearing is held stationary the same as the nut and the thrust-screw and thrust-pin operate the same as if the nut were screwed upon the end of the shaft. (See j' in Fig. 1.)

It is obvious that the bearings for the 120 shaft can be formed with bolted caps; but such construction is not necessary if the shaft be made to pull out of the bearings longitudinally, as shown in Fig. 1, where the shaft next the friction-driver of the drum F 125 is larger than at any other point, so that it can be pulled through its bearing by first removing the thrust-key N and the cap j if the latter be attached to the shaft.

In the drawings, steam-cylinders B are 130

shown, and a crank-shaft C, connected by gearing with the friction-drivers; but the invention is applicable to hoisters actuated by electric motors or any other motive power, as the invention relates to the drum and its shaft and not to the motor agent. Electric hoisters are now often used in hoisting materials to the top of tall buildings when in process of erection, and the enormous length of the rope which is wound upon the drum in such cases necessitates a rapid speed of the drum to avoid great loss of time in transmitting the load. My invention is applicable to such hoisters and is of great value in removing the friction between the thrust-pin and the thrust-screw, which has heretofore limited the speed of hoisting-drums.

The hoisting-drum Q is shown with high flanges at the ends, as the end of the rope is fastened to the hoisting-drum and wound thereon; but the hauling or traversing drum F is represented with low flanges, such as are used in traversing the carriage upon a cable-way, in which case the coils do not accumulate upon the drum, as an endless rope is used and only a few coils are carried around the hauling-drum, which coils are constantly crowded toward one of the end flanges by the winding of the coils.

30 The invention is applicable to drums of all kinds which turn loosely upon the shaft and are driven by a friction-driver.

Having thus set forth the nature of the invention, what is claimed herein is—

35 1. The combination, with a shaft having a drum or spool fitted to turn loosely thereon and provided upon its inner end with a friction-seat, of a friction-driver fitted thereto and adapted to turn loosely upon the shaft, 40 means for rotating the friction-driver, an antifriction thrust-bearing upon the shaft to prevent the end movement of the friction-driver, and an antifriction thrust-bearing upon the shaft at the outer end of the drum 45 with means for pressing one of the thrust-bearings toward the other to engage the drum and friction-driver, whereby the friction-driver and drum, when engaged rotate together upon a stationary shaft between 50 antifriction thrust-bearings.

2. The combination, with a shaft having a drum or spool fitted to turn loosely thereon and provided upon one end with a friction-seat, of a friction-driver fitted thereto and 55 adapted to turn loosely upon the shaft, and having a hub with renewable bushing, a spiral spring encircling such hub between the drum and the friction-driver to separate them normally, an antifriction thrust-bearing upon the shaft to prevent end movement of the friction-driver, means for rotating the driver, and an antifriction thrust-bearing applied to the outer end of the drum, with means attached to the shaft for pressing such 60 bearing against the drum to engage it with the

friction-driver, whereby the friction-driver and drum when engaged rotate together upon a stationary shaft.

3. The combination, with a shaft having a drum or spool fitted to turn loosely thereon 70 and provided upon its inner end with a friction-seat, of a friction-driver fitted thereto and adapted to turn loosely upon the shaft, means for rotating the friction-driver, an antifriction thrust-bearing upon the shaft to 75 prevent end movement of the friction-driver, an antifriction thrust-bearing applied to the outer end of the drum, the shaft having a transverse slot adjacent to the outer flange of said thrust-bearing with key in the slot to 80 press upon the flange, and means attached to the end of the shaft for pressing the key toward such outer flange to engage the drum with the friction-driver, whereby the friction-driver and drum when engaged rotate 85 together upon a stationary shaft.

4. The combination, with a shaft having a drum or spool fitted to turn loosely thereon and provided upon its inner end with a friction-seat, of a friction-driver fitted thereto 90 and adapted to turn loosely upon the shaft, means for rotating the friction-driver, an antifriction thrust-bearing upon the shaft to prevent the end movement of the friction-driver, an antifriction thrust-bearing applied 95 to the outer end of the drum, the shaft having a transverse slot adjacent to the outer flange of said thrust-bearing with key in the slot to press upon the bearing, a hole extending from the slot to the end of the shaft with 100 thrust-pin therein, a nut secured upon the end of the shaft with screw-thread in line with such hole, and a screw fitted to the nut to press the thrust-pin upon the key, whereby the key, the pin, the nut and the screw are 105 stationary with the shaft, and the drum and friction-driver when engaged revolve together upon the shaft.

5. The combination, with a shaft having a drum or spool fitted to turn loosely thereon 110 and having a friction-seat upon the inner end, of a ball-race secured upon the shaft adjacent to such end, a friction-driver fitted to turn loosely upon the shaft between said drum and ball-race and having a corresponding ball-race with balls fitted thereto, means to rotate the friction-driver, a ball-race applied to the outer end of the drum, a corresponding ball-race movable longitudinally upon the shaft with balls fitted to the said 115 races, and means attached to the shaft for moving the last-mentioned ball-race to press the drum toward the friction-driver, whereby the friction-driver and drum rotate together upon a stationary shaft.

6. The combination, with a shaft having a drum or spool fitted to turn loosely thereon and having a friction-seat upon the inner end, of a ball-race secured upon the shaft adjacent to such end, a friction-driver fitted to turn 120

loosely upon the shaft between said drum and ball-race and having a corresponding ball-race with balls fitted thereto, means to rotate the friction-driver, a ball-race applied 5 to the outer end of the drum, a corresponding ball-race movable longitudinally upon the shaft with balls fitted to the said races, the shaft having a transverse slot adjacent to the movable ball-race with key therein and 10 hole extended from the key to the end of the shaft, a thrust-pin fitted to such hole, a cap screwed upon the end of the shaft and having threaded nut therein, and a screw fitted to the nut with point adapted to press upon the 15 thrust-pin, whereby the outer ball-race, the key, the pin, the nut and the screw are stationary with the shaft, and the drum and friction-driver when engaged revolve together upon the shaft.

20 7. The drum-fixtures for application to the bearings upon the opposite sides of a hoister-frame, comprising a shaft with journal near one end for clamping in the bearing, a thrust-

bearing secured upon the shaft adjacent to such journal, a friction-driver fitted to turn 25 upon the shaft in contact with such thrust-bearing, a drum fitted to turn upon the shaft with friction-seat to engage the friction-driver, a journal upon the opposite end of the shaft to fit the opposite frame-bearing, a 30 thrust-bearing between such journal and the end of the drum, and means attached to the outer end of the shaft for pressing such thrust-bearing against the drum, whereby the journals of the shaft are adapted to 35 clamp rigidly in the bearings and the drum and friction-driver when engaged revolve together upon the shaft.

In testimony whereof I have hereunto set my hand in the presence of two subscribing 40 witnesses.

ASHER LAMBERT.
